[57] CLAIM

The ornamental design for a key handle applique set, as shown and described.

DESCRIPTION

FIG. 1 is a perspective view of a key handle applique set showing my new design;

FIG. 2 is a front elevational view thereof, the rear being identical in appearance;

FIG. 3 is a top plan view thereof;

FIG. 4 is a left side elevational view thereof;

FIG. 5 is a right side elevational view thereof; and,

FIG. 6 is a bottom plan view thereof.

The broken-line disclosure of a key in the view is for illustrative purposes only and forms no part of the claimed design.
